ARON HELFANT, OF BUFFALO, NEW YORK.

CARPENTER'S HINGE-GAGE.

1,179,723.

Specification of Letters Patent. Patented Apr. 18, 1916.

Application filed May 26, 1915. Serial No. 30,503.

To all whom it may concern:

Be it known that I, ARON HELFANT, a citizen of the United States, residing at Buffalo, in the county of Erie and State of New York, have invented new and useful Improvements in Carpenters' Hinge-Gages, of which the following is a specification.

This invention relates to a carpenter's gage for facilitating the accurate cutting of the hinge-mortises of doors, windows and the like.

It is the object of my invention to produce an inexpensive device of this character, which can be readily adjusted to gage hinge-mortises of different dimensions.

In the accompanying drawings: Figure 1 is a perspective view of the gage as applied to a door, which latter is shown in dotted lines. Fig. 2 is a transverse vertical section 20 of the same, showing a mortise cut in the door. Fig. 3 is a top plan view of a modified form of my invention. Fig. 4 is a transverse vertical section on line 4—4, Fig. 3. Fig. 5 is a top plan view of another 25 modification of the device. Fig. 6 is a transverse vertical section on line 6—6, Fig. 5. Fig. 7 is a fragmentary perspective view of a door jamb having the usual rabbet, showing the use of the gage plate and 30 marker. Fig. 8 is a similar view of a door jamb without a rabbet, showing the use of the gage plate and marker. Fig. 9 is a similar view of a door and the gage plate and marker, showing the manner of taking 35 the measurement of the door-mortise, preparatory to marking the jamb-mortise.

Similar characters of reference indicate corresponding parts throughout the several views.

Referring to Figs. 1 and 2, 1 and 1^a indicate a pair of clamps adapted to embrace the edge of a door 2 or other part to which hinges are to be applied, such as a sash. These clamps are provided with clamping 40 screws 3 which engage one side of the door, and opposing lugs or jaws 4 which engage the opposite side thereof. Carried by a bracket or rearward extension 5 of each clamp is a chisel-rest or platform 6 on which 45 one or both of the clamps are adjustable laterally or lengthwise of the door to gage the length of the hinge-mortise. The inner faces of the clamps form gage-walls against 50 which a chisel is placed for cutting the ends of the mortise, while the platform serves as a rest for the chisel in gaging and cutting

the mortise to the proper depth. At its rear edge, the chisel-rest has a depending flange 7 through which pass thumb screws 8 which engage screw threaded openings in 60 the adjacent ends of the brackets 5. The chisel-rest is provided in its front edge, near one end, with a notch or seat 9 adapted to receive the neck 10 of the clamp 1, while the opposite end portion of the rest is provided with a series of similar notches or 65 seats 11 adapted to receive the neck 10 of the other clamp 1^a. The depending flange 7 is provided with a series of openings 12 which register with the notches 11 of the 70 rest and one or another of which is adapted to receive the right hand thumb screw 8. By this series of notches 11 the clamp 1^a, upon removing the last-named screw from 75 its bracket 5, can be readily adjusted toward or from the clamp 1, the screw being replaced in the appropriate opening 12 to again secure the clamp in position. The notches 11 and holes 12 are arranged at different predetermined distances from the 80 notch 9 and may be graduated to fractions of an inch, so that the clamp 1^a may be adjusted to gage hinge-mortises of different 85 lengths.

To prevent upward displacement of the front portion of the chisel-rest on the clamps, the necks of the latter are provided in their rear edges with notches 13 which receive the notched front edge of the chisel-rest, as best shown in Fig. 2.

For the purpose of gaging the depth of the mortise, the clamps are provided with adjustable gage-stops preferably consisting of thumb or set screws 14 arranged in threaded openings in the yokes of the clamps 95 and adapted to engage the edge of the door to determine the elevation of the chisel-rest with reference to said edge, the depth of the mortise being greater or less according as the rest is lowered or raised.

The breadth of the mortise is gaged by a suitable gage plate and marker 15. This plate is provided at its longitudinal edges with oppositely-bent flanges 16, 17, the outer corners of which are preferably provided with markers or scoring-spurs 18 for a purpose hereinafter described. When this plate is used to gage the width of a door-mortise, it is clamped between the door and the clamping screws 3 with its flange resting 110 against the edge of the door, as best shown in Fig. 2. In this position, the inner edge

of said flange forms a gage against which the chisel is placed to cut the mortise to the proper width. The plate serves not only as a gage for this purpose but also as a protective covering for the door, which prevents marring thereof by the clamping screws.

It will now be understood that in the use of this device, for example to cut a hinge-mortise in a door, the carpenter first places the adjustable clamp 1^a in the notch 11 corresponding to the length of the desired mortise, securing the clamp in position by its thumb screw 8. The gage plate is next applied to the door and the clamps are passed over the edge of the door, after which the set screws 14 are adjusted to locate the chisel-rest 6 the proper distance below the edge of the door, and finally, the clamping screws 3 are tightened. By placing the chisel against the four gage-faces formed by the inner sides of the clamps, the chisel-rest and the flange 17, the mortise can be quickly and squarely cut in an obvious manner, insuring the accurate attachment of the hinge and the proper hanging of the door.

In addition to the spurs 18 the gage plate 15 is preferably provided on its flange 16 with a longitudinally adjustable gage bar 19 adapted to coöperate with the spurs 18 of said flange. In the construction shown, this bar is secured to said flange by a screw stud 20 passing through a longitudinal slot 21 in the flange 16 and a nut 22 engaging with the stud. This bar and the spurs enable the gage plate to be used for the additional purpose of gaging or measuring hinge-mortises for door jambs.

In the case of a door jamb 40 having the usual stop 41, as shown in Fig. 7, the gage plate is placed with its body portion against that edge of the stop nearest the mortise to be cut, and its flange 17 against the jamb. The plate is then slid along the stop to draw or score the gage-line 41^a, which defines the inner wall of the mortise to be cut.

In the case of a door-jamb having no stop, as shown in Fig. 8, the measurement for the breadth of the mortise is taken from that of the door, previously mortised (Fig. 9), by placing the gage-plate transversely against the door with the spur 18 of the flange 16 in register with the inner wall of the door-mortise, as shown in the last-mentioned figure, and then adjusting the gage-bar 19 to bring its opposing end against the side of the door. The gage plate is then reversed end for end and transferred to the door-jamb 42 with the last-mentioned end of its gage bar 19 bearing against the side of the jamb, as shown in Fig. 8, and the gage-plate is moved along the side of the jamb to cause the spur or marker to draw the gage line 43. The mortise in the door thus corresponds exactly to the mortise in the jamb.

Referring to Figs. 3 and 4, which show a modified form of the invention, the chisel-rest or platform 23 is provided near one end with front and rear notches or seats 24, 25, adapted to receive respectively the neck of 70 the clamp 1^b and an upwardly-projecting lug 26 of the bracket 27, of said clamp. The opposite end-portion of the chisel-rest is provided with a series of similar notches 28, 29, adapted to receive respectively the 75 neck of the adjustable clamp 1^c and a corresponding upwardly-projecting lug 26^a of the bracket 27^a of said clamp, the latter being adjusted toward and from the first-named clamp by placing it on one or another set of said 80 last-mentioned notches. The lugs 26 and 26^a are undercut, as shown at 26^b, to hold the chisel-rest down in place upon the clamp bracket.

Referring to Figs. 5 and 6, showing another modification of the invention, the chisel-rest 33 is provided at one end with a notch 34 adapted to receive the neck of the clamp 1^d, while the opposite end portion of the rest is provided with a series of 90 similar notches 35 arranged at predetermined distances from the notch 34 and adapted to receive the neck of the other clamp 1^e, which is adjustable toward and from the first-named clamp, as in the constructions previously described. The parts are held together by means of screws 36 entering openings 37 in the chisel-rest and screw-threaded openings 38 in the brackets 39 of the clamps. In this construction, the 100 brackets 39 may be shorter than the width of the chisel-rest.

By the use of this improved device, hinge mortises can not only be cut with absolute accuracy, but an important saving in time 105 is effected.

I claim as my invention:

1. A carpenter's gage, comprising clamps adapted to embrace the edge of a door and forming gage-members, a chisel-rest carried 110 by said clamps, said clamps being mounted on said rest and adjustable relatively to each other to vary the distance between them, and means for holding the clamps in position on the rest.

2. A carpenter's gage, comprising a pair of clamps adapted to embrace the edge of a door and having brackets, said clamps forming gage-members, and a chisel-rest mounted on said brackets, one of said 120 clamps being adjustable on said rest relatively to the other clamp.

3. A carpenter's gage, comprising a pair of clamps adapted to embrace the edge of a door and carrying brackets, a chisel-rest mounted on said brackets, said rest having a longitudinal series of seats adapted to receive a member of one of said clamps, and means for removably retaining said clamp-member in one or another of said seats. 130

4. A carpenter's gage, comprising a pair of clamps adapted to embrace the edge of a door and having brackets, a chisel-rest mounted on said brackets and provided at 5 its front edge with notches and at its rear edge with a flange, said clamps engaging a pair of said notches, and means for securing said flange to said brackets.

5. A carpenter's hinge gage, comprising a 10 pair of clamps adapted to embrace the edge of a door and having brackets, a chisel-rest mounted on said brackets, said rest being provided in its front edge with notches adapted to receive the necks of said clamps, 15 the neck of each clamp having a notch interlocking with said rest to prevent vertical displacement thereof on the clamps, and means for retaining the clamps in the notches of said rest.

6. A carpenter's gage, comprising a pair 20 of clamps adapted to embrace the edge of a door, a chisel-rest carried by said clamps, said clamps being relatively adjustable on said rest, and a gage-plate adapted to be interposed between said clamps and the door 25 on the side opposite that at which the chisel-rest is located, said plate having a gage-flange arranged to rest against the edge of the door.

7. A carpenter's gage, comprising a pair 30 of clamps adapted to embrace the edge of a door, a chisel-rest mounted on said clamps, and gage-screws carried by the yokes of said clamps and adapted to bear against the edge of the door for determining the position of the chisel-rest relative to said edge. 35

ARON HELFANT.
